UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

CORE FOR STEREOTYPE-PLATE-CASTING BOXES.

Application filed December 26, 1922, Serial No. 609,046. Renewed December 27, 1926.

This invention relates to the core or casting cylinder used for casting stereotype printing plates, particularly those of curved form.

5 The principal object of the invention is to provide a core of such a character that the cooling of the cast stereotype metal will be facilitated thus saving time in completing and ejecting the cast; that the cast itself will 10 have a better surface with fewer indentations upon it than when cast against an ordinary cast iron core; and that the lead, tin and antimony in the molten metal will not alloy with the metals of the core.

15 Reference is to be had to the accompanying drawings, in which

Fig. 1 is a side view partly in section of one type of curved stereotype printing plate mold adapted to be employed in connection 20 with this invention;

Fig. 2 is a sectional view on the line 2—2 of Fig. 1 and

Fig. 3 is a similar view of another form 25 of core to which this invention can be applied.

The invention is shown as applied to the core 10 of a casting box which is adapted to cooperate with a back 11. The back can be made of any of the usual types, and as a 30 matter of fact the core can also, and this invention is universally applicable to all casting boxes for use in casting stereotype metal or other metal of similar composition, as for example a segmental core 20 shown in 35 Fig. 3.

It has been found in practice that the cast iron back and core of the ordinary molds are slow in conducting the heat away and have to be cooled internally by water if it 40 is desired to produce stereotype plates with any degree of rapidity. Even then it is the cooling of the plates that limits the speed of the machine. As is well known, this process is carried out now with automatic or 45 semi-automatic machines which eject, trim, and shave the cast plate rapidly, but in which the cooling and setting of the cast metal is the time limiting factor.

I have also found that if a brass core is used the copper thereof will alloy with the 50 metals of which the stereotype metal is composed so that the core will soon go to pieces. This also changes the composition of the casting and makes it harder to machine.

I find that I can overcome these several 55 difficulties and also produce a much better cast surface on the stereotype plate, one that is smoother, and contains fewer blow-holes and depressions, by making the core of aluminum or an alloy in which aluminum is the chief 60 ingredient. The high conducting powers of aluminum are well known and this metal, therefore, conducts the heat away from the molten metal more rapidly than the other metals above mentioned. But I find also that 65 it has an especially agreeable effect upon the stereotype metal in cooling, giving it a better surface against the core, thereby producing a stronger cast because there are fewer depressions that are caused by bubbles of air 70 or gas in the molten metal.

This is useful in connection with all kinds of stereotype metal molds, but particularly 75 valuable in connection with casting machinery in which the various operations are started as soon as the cast is cooled and which have to wait for that.

In such machines further progress in increasing the output is seriously impeded by 80 the fact that heretofore it has seemed that the limit had been reached in reducing the time of cooling. I prefer to cool the core and back just as has been done heretofore so as to get the full benefit of that effect also.

Although I have illustrated only two 85 forms of the invention and described it as used in connection only with certain types of stereotype plate molds, I am aware of the fact that it is capable of general use within the scope of this invention as expressed in the claims. Therefore I do not wish to be limited in these respects, but what I do claim is:—

1. As an article of manufacture, an aluminum stereotype plate casting core for increasing the rapidity of cooling the casting. 95

2. As an article of manufacture, a core for a curved stereotype printing plate mold composed mainly of aluminum.
3. As an article of manufacture, a stereotype printing plate casting core having an aluminum casting surface and consisting of aluminum all the way through.
4. As an article of manufacture, a stereo-

type printing plate casting mold having a back, and a core provided with a convex surface and formed of a metal containing a large percentage of aluminum. 10

In testimony whereof I have hereunto affixed my signature.

HENRY A. WISE WOOD.
